The ornamental design for a boiler low water cutoff/pump controller probe, as shown and described.

DESCRIPTION

FIG. 1 is a first perspective view of a first and second embodiment of a boiler low water cutoff/pump controller probe showing my new design;

FIG. 2 is a second perspective view of the first and second embodiment;

FIG. 3 is a right side elevation view of the first embodiment; FIG. 4 is a right side elevation view of the second embodiment;

FIG. 5 is a front elevation view of the first and second embodiment;

FIG. 6 is a left side elevation view of the first embodiment; FIG. 7 is a left side elevation view of the second embodiment;

FIG. 8 is a rear elevation view of the first embodiment;

FIG. 9 is a rear elevation view of the second embodiment;

FIG. 10 is a top plan view of the first embodiment;

FIG. 11 is a top plan view of the second embodiment;

FIG. 12 is a bottom plan view of the first embodiment; and,

FIG. 13 is a bottom plan view of the second embodiment. The first embodiment discloses a boiler low water cutoff/pump controller probe with three pegs on its rear portion as shown in FIGS. 1, 2, 3, 5, 6, 8, 10 and 12. The second embodiment discloses a boiler low water cutoff/pump controller probe with one peg on its rear portion as shown in FIGS. 1, 2, 4, 5, 7, 9, 11 and 13.

The stippled lines showing a bottle in FIG. 1 are included for the purpose of illustrating environment and form no part of the claimed design. The lightweight broken lines showing the eight small circles in FIGS. 1, 2, 5, and 8-13 are for the purpose of illustrating unclaimed elements and form no part of the claimed design.
